JOSEPH BIJUR, OF NEW YORK, N. Y., ASSIGNOR, BY MESNE ASSIGNMENTS, TO AUTO RESEARCH CORPORATION, A CORPORATION OF DELAWARE

CENTRAL LUBRICATION

Application filed December 27, 1924. Serial No. 758,361.

My present invention relates to central lubrication and it particularly relates to the lubrication of some or all of the bearings of the various linkages or operating connections capable of broad application in automotive vehicles and in other mechanism. Although the present invention is illustratively applied to the lubrication of brake-operating linkages, it is by no means restricted to such application.

It is among the objects of the invention to prevent rattle, to reduce wear and to render more easy the operation of the brakes of motor vehicles and more especially to provide effective and convenient lubrication for those pivot bearings of the linkage for operating the rear wheel brakes, which by reason of their large number, their small size and their inaccessibility have not been lubricated heretofore, with any degree of regularity.

The invention in a preferred application is concerned with the lubrication of the linkage referred to, by operation from the frame, and in one aspect is concerned more especially with the construction and arrangement of conduit, by which the lubricant is passed from the frame to an axle or other part moving relative thereto, particularly to the parts of the brake mechanism carried on the rear axle.

The supply conduit, it is apparent, should accommodate the rise and fall of the rear axle relative to the frame, which occurs as the springs flex during travel of the vehicle. My invention has among its objects to provide a serviceable conduit of low cost, which provides the required yield or flexibility where yield should occur, which is not subject to whipping, and which is substantially proof against rupture or leak from vibration of the moving vehicle even in hard usage. My invention provides a conduit in the above relation, the parts of which are not likely to be bent or broken off by the usual impacts encountered in ordinary usage, and which, while accommodating the various relative movements without undue strain at any part of the conduit is, nevertheless, mechanically so strong and is retained in place upon the

vehicle structure so securely as not to be torn loose by the driving of the vehicle through brush or bushes, which will suffer no substantial injury from pelting by ice or loose stones that may be thrown up from the road by the movement of the vehicle thereon, which will not be torn off or damaged by mud frozen thereonto, and which will not be disturbed by handling in cleaning the vehicle.

The desired results are accomplished according to the present invention by extending the lubricant conduit lengthwise of the usual linkage, by which the brake is operated from the usual pedal or brake lever. The lubricant is advantageously conveyed through the length of the linkage, the various elements of which are bored or made hollow for the purpose desired, so that the lubricant duct is not only protected within the linkage, but, being an integral part thereof, accommodates as does said linkage, the movement of the rear axle relative to the frame.

Preferably the entire linkage is such that the lubricant conduit is completely enclosed therein and accordingly protected thereby, the various parts being structurally related to inherently establish passages for lubricant in correct non-leaking relationship, and to lubricate the various bearing surfaces in the length of the conduit, all in the absence of any distinct lubricating attachments or connections apart from the mechanical structural assembly.

A familiar type of brake linkage includes an arm depending from the operating rock shaft to which is pivoted the forward end of a pitman link, the rear end of which is pivoted to a lever on the brake drum or shield. Objects of the invention are to convey the lubricant reliably lengthwise of such linkage, without interfering with the normal operation of the linkage or with the adjustments ordinarily effected in the length of the pitman rod. Other objects are to lubricate with oil passed along the linkage, the various bearings thereof including those at the opposite ends of the pitman link, and without the need for unduly tightening said bearings or making them more bulky or providing pro-

trusions thereon in order to avoid loss or leak of lubricant from the bearings.

According to my invention, the pivot bearing of the pitman link with respect to the arm 5 on the rock shaft, from which it is operated, is in a special terminal fitting at the forward or upper end of the tubular pitman, and the bearing with respect to the lever at the brake is similarly disposed in a special terminal 10 fitting at the lower or rear end of said pitman. Preferably, the lubricant is supplied to the linkage through a fixed inlet associated with the rock shaft whence it drains through a duct longitudinally of the arm thereon to the upper or forward end of the pitman, thence longitudinally through the pitman tube to the lower bearing thereof and thence through an appropriate duct at the lever to bearings at the brake drum or brake shield.

20 To avoid the loss of lubricant at any of the various joints in the linkage, the pivot pin of each said joint is preferably rigid with the encircling eye or terminal of the linkage element through which the lubricant is fed thereto and affords a duct for the lubricant extending outward to the bearing surface in the eye or terminal pivoted thereon of the succeeding element in the linkage train. Each 25 mechanical element in the train that has a bearing about a pivot pin, preferably has a duct so related to the pin that the lubricant draining from the bearing will naturally pass on into the duct for flow to the bearings, rather than to leak past the ends of the bearing to the road. By this arrangement, although the 30 bearing structure is unenclosed the lubricant at the bearing surface tends to spread outward rather than inward and thus inherently to exclude or wash out any dust or dirt 35 that might otherwise be drawn into the bearing. The relatively rocking elements of the bearing preferably have a telescoping relation, to render more difficult the entry of dust or dirt and in addition a peripheral groove 40 is provided on the inner of the elements adjacent the edge of the outer one, so that dirt or dust will tend to drop therethrough from the bearing rather than to work its way thereinto.

45 In other embodiments, an exit terminal of each mechanical element in the linkage train extends into the inlet terminal of the next element in the train, said inlet terminal constituting a receptacle in which the bearing is 50 contained, which receptacle drains through a duct in the latter mechanical element to supply other bearings.

55 In the lubrication of an embodiment of brake in which rock shafts at the brake shield and parallel to the axle transmit the hand and foot braking impulses respectively, through pitmen pivoted to levers mounted on the inner ends of said rock shafts, the lubricant supplied through each of said pitmen is 60 preferably passed onward through the asso-

ciated lever, to lubricate the bearings therefor.

The invention from another aspect is concerned with the local distribution of lubricant from an inlet at the brake to the various bearings associated therewith and substantially regardless whether said inlet is supplied through the brake operating pitmen or otherwise.

70 The invention provides convenient means for reliably lubricating all or any number of said bearings without the need for selective manipulations or direct manual access to the individual bearings, and without conduits protruding or projecting, so as to be likely to be torn loose in ordinary use of the vehicle.

75 To this end, an inlet fixed on the brake shield may supply an appropriate flexible conduit which is connected at its opposite end preferably to the uppermost bearing of the associated linkage, or alternatively a rigid pipe may be mounted to drip through an air gap onto such uppermost bearing, the lubricant being delivered therefrom to the other 80 bearings, either through appropriate bores, ducts or conduits, or by the capillary action of layers of felt included in the linkage structure.

Referring now to Figs. 1 to 4 of the drawings, I have shown a construction of rear wheel brake and of the operating linkage

therefor, which, in general outline, is known, and for a better understanding of the invention, will be briefly described. The channel side member C of the vehicle mounts a pair of brake operating cross shafts 10 and 11, the

former for the external or foot brake, the latter for the internal or hand brake, operated respectively by the brake pedal and the brake lever (not shown). An arm 12 has a hub 13 fixed over the cross-shaft 10, and oscillating therewith as the pedal is operated. The low-

er end of said arm is pivoted to a pitman rod 15, sloping downward and pivoted at its lower end at 16 to the upper end of the curved lever 17 pivoted at 18 to a yoke 19 rigidly mounted at the exterior of the brake band 20. Pivoted at 21 to the brake drum lever is the usual clamp rod 22 encircled by a compression spring 23, which normally maintains the outer brake band in open or non-braking position, by reacting at one end against a supporting eye 24 outside the drum, and at the other against a lug 25 on the band. When a braking impulse is applied, lever 17 is rocked in clockwise direction to draw the clamp rod 22 downward causing the brake band to clasp the drum.

The internal or hand brake includes a similar construction of arm 26 and rod 27, the lower or inner end of the pitman link being pivoted to a lever 28 rigid with the rock shaft 29, which carries a shorter lever 30 also rigid therewith and transmits an impulse through an operating link 31 to the joint 32 of a toggle composed of links 33 and 34 pivoted respectively to brackets 35 and 36, at the ends of the internal brake band. The construction as thus far described, taken by itself, is entirely conventional and well known.

By my invention, means is provided for effectively lubricating various bearings associated with the brake linkage. Lubricant is preferably admitted through a pipe 37 from a centralized lubricant station and thence through a flow control fitting 38 to a bore 40 in the bearing bracket 39 which supports the rock shafts, said bore extending upward to a horizontal duct 41 from which the bearings of both of the rock shafts are lubricated. The control fitting 38 may be a drip plug of my invention, the precise construction of which is not material to an understanding of the present invention, it being merely noted that a multiplicity of similar drip plugs at various parts of a centralized chassis lubricating system will each feed a predetermined proportion of a charge propelled under pressure from a common source. The outlets 41' of duct 41 are restricted to substantially control the lubricant draining to the respective bearings. The foot or external brake is supplied from duct 41 through an oblique bore 42 in the rock shaft, which drains much of the lubricant admitted through the bore 41' to the upper end of a longitudinal duct 43 in the arm 12. The arm 12 being friction-fitted and secure upon the shaft, no lubricant is lost in the passage from the oblique duct 42, while slight seepage of lubricant past the inlet to said oblique duct serves to lubricate the bearing of the rock shaft 10.

In the preferred construction shown, the pitman 15 constitutes a metal tube through which lubricant can be passed, the terminal 46 threaded as at 47 over the upper end thereof of having an eye 48 aligned with the eye 49 at

70

75

85

90

95

105

110

115

120

125

130

the lower end of the arm 12. A pivot pin 50 for the eyes 48 and 49 has a head 51 adjacent to the eye 48, and a shoulder 51' substantially flush with the opposite face of said eye and drawn against eye 49, which latter has a correspondingly smaller bore to fit about the correspondingly reduced part of the bolt shank beyond shoulder 51'. A nut 53 threaded on the end of bolt 50 is locked against the eye 49 by a lock washer 54, and presses said eye against shoulder 51'.

Preferably a copper washer 52 is pressed by the end of the pitman tube 15 into the socket of the terminal 46, said softer metal forming an oil-tight closure to prevent the possible leakage of lubricant past the screw threads 47. The longitudinal duct 43 in the arm 12 delivers to a peripheral groove 60 aligned therewith in the shank of the pin 50, which latter through a radial bore 59 communicates with a longitudinal bore 57 plugged as at 58 at the outer end. A radial bore 56 taps said longitudinal bore in the region of the rod eye 48, and delivers to a peripheral groove 55 thereat, from which said bearing, in turn, is lubricated.

The eye 49 of arm 12 is pressed by the nut 53 against the shoulder 51' on said bolt, so that said arm and said bolt are, in effect, a rigid unit. Preferably, the bolt, moreover, has a tight fit in said eye 49, so that all of the lubricant from the arm is effectively delivered into said bolt, the sole bearing surface being between the bolt and the rod terminal 48. Thus, the lubricant is delivered to the bearing surface first into bolt 50, thence radially outward to the encircling bearing eye 48, thereby providing, as will be apparent, reliable lubrication.

In the construction shown, the pivot 16 at the lower end of the pitman is lubricated by oil passed through the tube 15 from the upper bearing just described. In order to assure reliable delivery of the lubricant from the bearing 48—50 into the tube 15 and to guard against the escape of lubricant laterally from the bearing to the ground, rather than into said tube, it is desirable as shown, to form the shank 46 of the terminal offset with respect to the eye 48, the axial bore 61 thereof extending, as shown, substantially tangential to the lower surface of the pin or bolt 50. It will thus be seen that the lubricant which has passed through the duct 43 in the arm 12 and about the bearing surface of eye 48 will drain therefrom into the terminal bore 61 and thence lengthwise of the hollow pitman rod to the terminal at the opposite end thereof.

The terminal 16 at the lower end of the pitman rod has a construction analogous to that of the upper end, and is intended to function in substantially the same manner, but is specifically different, as will be apparent. In this case, as best shown in the sectional view, Fig. 3, the pin is of identical construction

with that at the upper end, except that its head 50' is against the eye 62 of the lever 17, the bearing surface occurring at said lever, while the eye 63 of the rod terminal is clamped between the lock washer 54' and the shoulder 51'. The construction of said pivot is otherwise identical with that shown in Fig. 2 and similar parts bear corresponding reference numerals primed. Thus, in this case, the lubricant delivered from the tube 15 past the axial bore 61' in the terminal enters the groove 55' about the pin 50' and proceeds thence through radial bore 59', longitudinal bore 57' and radial bore 56', outward to lubricate the bearing surface of the pin 50' in the eye 62 of the lever 17. To facilitate assembly, it is preferred to make the terminal 16 adjustable on the lower end of the pitman rod, by providing a substantial threaded length 64 on the tube, upon which the terminal 16 is screwed and secured by a nut 65 locked by a lock washer 66.

Excess lubricant from the bearing 62 may be passed onward to certain of the linkage, heretofore described, on the brake support plate. For this purpose, a preferred construction is shown in which the lever 17 is formed with an oblique bore 67 near its upper end, extending through a lug 68 and into this extends the upper end of preferably a hard metal pipe 69, said pipe terminating at its upper end, as shown, directly below the pin 50', so that the lubricant draining from the bearing 62 will naturally drop downward into said pipe rather than escape from the ends of the bearing. The pipe 69 as shown, is preferably curved close against the surface of the lever 17 and terminates at an upwardly extending end 70 delivering into the mounting bearing 18 of said lever. In the preferred embodiment, a longitudinal bore 71 through the lower end of the lever 17 delivers lubricant from the mounting bearing 18 to the bearing pin 21, upon which the clamp rod 22 is mounted.

It will be seen that the presence of the lubricating appurtenances set forth in no way alters the operation of the train of linkage between the pedal and the brake drum, while lubricant is reliably fed into bearing 40, thence longitudinally through ducts 42 and 43, thence to the pivot bearing 48, at the upper end of the pitman rod, thence through the upper terminal of the pitman to the lower terminal, thence lengthwise of the hand lever 17 to the mounting bearing 18 thereof and thence to the mount 21 of the clamp rod 22. Thus, all of said bearings are lubricated seriatim by flow of the lubricant successively from one to the other, each bearing intercepting sufficient oil for lubrication thereof. Loss of lubricant in transit is prevented, the entire residue in excess of the requirement of each bearing, passing onward in its travel to the

succeeding bearing. While in many automotive constructions on the market, the brake linkage slopes downward, as shown in the drawings, so that any lubricant admitted will promptly flow by gravity through the course set forth, it will be understood that even if the pitman rod were generally horizontal, the operation would take place substantially as described, while the vehicle is ascending a hill, during which time the pitman tube would, of course, slope downward, and any lubricant therein would then flow toward the brakes.

It will be seen that according to the arrangement disclosed, the brake linkage encloses and protects the oil duct through which lubricant passes from the frame to the bearings on the brake shield, said linkage accommodating the relative movement between the brake shield and the frame, as the vehicle springs compress and rebound. The linkage is substantially as stiff and as rugged as if devoid of lubricating appurtenances, and will, therefore, withstand the stresses incurred in use.

It will be noted that in the construction described, the impulse delivered through the operating arm 12 is along an axis not directly aligned with that of the tube 15, so that in braking operation, there might be a bending moment on the tube in addition to the tension strain. I prefer, as indicated in the drawings to leave a small clearance 72 between the encircling terminal 46 and the tube 15 beyond the threads 47, so that any bending moment on the tube will be distributed over the unthreaded length of terminal, so that a sharp bend of the tube adjacent to the threads is avoided.

The arm 26, pitman 27 and terminals thereof through which the internal or hand brake is operated are identical with those of the external or foot brake just described. However, the lever 28 with which the lower terminal of the hand operated pitman operates is straight, as heretofore described, and it is preferred in this connection to provide a bore 73 longitudinally of said lever to lead lubricant draining from the lower end of the rear pitman bearing downward to the mounting bearing 29 thereof.

For purposes of dust exclusion, I have a telescoping arrangement at various bearings. The hub 13 of arm 12, for instance, overlaps as at 74 the reduced extension 75 of the mounting bracket 39. Similarly as shown in Fig. 2, eye 48 overlaps at one face thereof as at 76, the head of pin 51, and at the other face as at 77 the correspondingly reduced extension on the contiguous eye. A similar arrangement is shown in Fig. 3. By this arrangement, dust, dirt or water would be more likely to drop off than to work into the bearing surface.

In Figs. 2a and 2b is shown a substitute

for the form of joint shown in Fig. 2, which is of simple construction, yet reliable in action. Corresponding parts bear the same reference numerals as in Fig. 2 with the exponent "a". In this embodiment, the pin 50a has a head 51a provided with a flat f' coacting with a corresponding lug f' in lever 12a to align radial bore 56a in said pin with the longitudinal bore 43a in the arm, thereby dispensing with the peripheral groove 59 provided in the embodiment of Fig. 2. The longitudinal bore 57a in the pin 50a delivers through a substantially horizontal radial bore 59a into the longitudinal bore 61a (Fig. 2b) of the terminal fitting 48a. Bores 59a and 61a are in alignment and the latter is of larger diameter than the former. The eye 48a of the upper terminal fitting is retained against substantial longitudinal shifting by the shoulder s of the bolt at one end and by the nut 53a at the other. To assist in excluding dust from the bearing, the eye 48a is provided with flanges 8 and 9 extending therebeyond peripherally about the corresponding portions of the bolt shank and nut respectively and extending respectively part way across a peripheral groove 8' in the bolt, and a similarly grooved hub 9' integral with the nut.

In assembling the joint, it will be understood, that the pin 50a properly aligned by means of the flat f' is secured by a drive fit in the eye of lever 12a. The terminal eye 48a is telescoped with a bearing fit over the protruding part of the bolt, in which assembly, the bore 59a necessarily registers with bore 61a whereupon the nut 53a is applied and drawn tight and then loosened slightly to avoid jamming eye 48a, and is then secured by a cotter pin or similar lock.

The lubricant, it will be understood, passes through the longitudinal bore 43a directly into the pin 50a without leakage, thence longitudinally of the pin and outward through the horizontal bore 59a directly into the terminal bore 61a, a part passing laterally from the end of the horizontal bore 59a to lubricate the bearing of eye 48a at the upper end of the pitman. Lubricant is thus effectively passed to the pitman terminal from the pin 50a without the use of the offset construction shown in Fig. 1. Dust falling onto the joint, it will be seen, will more readily pass peripherally downward along the grooves 8' and 9' and drop from the construction, than to work its way into the bearings which are, accordingly, relatively dust-proof.

It will be understood that the bearing at the lower end of the pitman, as shown in Fig. 1, could also be modified in a similar manner (not shown) to fix the pin 50' by means of a flat and to eliminate the peripheral grooves. Such modification will be apparent to those skilled in the art from the construction described.

In the constructions shown in Figs. 1 to 4, it will be seen that while the bearings are substantially open, that is unencased in boots or enclosures, yet the lubricant passes reliably through the bearings and linkage elements consecutively, adequately lubricating said bearings without appreciable leakage thereat and without the entry of dust, dirt or other foreign matter or particles into the course of lubricant flow. Apart from the fact that the bearings are so constructed that foreign matter would not tend to work its way thereinto, it should be noted that the lubricant spreads outward, along each of the bearing surfaces, thus, tending to wash any dirt or dust outward rather than to draw it inward into the bearing.

In Figs. 5 and 6 is shown a preferred mode of lubricating another type of brake rigging, including a forging 78 riveted to the brake shield 79 in order to provide bearings 80 and 81 respectively for the outer ends of rock shafts 82 and 83 through the former of which the external or foot brake is operated and through the latter, the internal or hand brake. The inner ends of the rock shafts are lodged in bearings 84 and 85 disposed in a mounting bracket 86 therefor, rigid with the axle 87. The rock shaft 83 has a cam 88 at its outer end coating with the brake shoes (not shown) of the internal brake in the familiar manner and at its inner end, said rock shaft has rigid therewith a lever 89 to which is connected the terminal 90 on the lower end of pitman rod 91 through which the braking impulse is transmitted. The rock shaft 82 for the foot brake is operated through a similar construction of lever 92 and pitman 93 having a terminal 93'. In order to transmit the braking impulse to the external brake rigging, the rock shaft 82 has rigid therewith near its wheel or outer end, an upstanding lever 94 which is connected by a transmitting link 95 to the upper end 96 of a curved lever 97 anchored as at 98 to the brake band 99, and acting upon a clamping rod pivoted thereto as at 98' in manner identical with the arrangement previously described and shown in Fig. 1. The link 95 is pivoted at one end as at 109 to lever 94, and at the opposite end as at 110 to lever 97.

For the lubrication of the various bearings thus far described, I provide three courses of lubricant flow in parallel with each other and preferably all supplied from a single ultimate source or station. The first course comprises the tube 93 which preferably has an arrangement of terminal (not shown) at its upper end identical with that shown in Fig. 2 or Fig. 2a and delivers the lubricant through the terminal 93' at the lower end, which may be of the type shown in Fig. 3, into the bearing at the upper end of lever 92. The lubricant thence flows outward through radial bore 100 and downward

through a longitudinal bore 101 in lever 92 into an axial bore 102 in the rock shaft 82 which empties by way of a radial bore 108 in said rock shaft to bearing 84. The second course of lubricant corresponds closely to that just described, the lubricant passing from the terminal 90 through a corresponding path (not shown) and delivering to bearing 85 by way of bore 104 radially of shaft 83.

The pivot bearings 109 and 110 of the connecting link 95 as well as the bearings 80 and 81 and preferably also the bearings 98 and 98' are supplied with lubricant through a third course now to be described. For this purpose, a flow control fitting 111 is fixed on the brake shield 79 and may be supplied through a pipe 112 from a source of lubricant on the frame. An appropriate lubricant conductor 113 to be described in detail below, which is of flexible or yielding character to accommodate the movement of the link, is connected at its outlet to a lateral lug 123 on the upper end or eye of lever 94, delivering through a duct 122 to a bolt or pin 115 forming a bearing for eye 109 on the rear end of link 95. The construction of the pivot bearing 115 is similar to and on the principle of that of Fig. 2, preferably substantially the construction of Fig. 2a and need, accordingly, not be described in detail.

A part of the lubricant from bore 122 will pass through bearing 109 which it lubricates in the manner clear from the description of Fig. 2a, thence passes onward through a bore 114 longitudinally of the link 95 to lubricate the bearing 110 at the opposite end thereof. Here also, I may employ the type of pivot shown in Fig. 2a, the pin 116 being rigid, as shown, with respect to the link eye 110 and affording a bearing therewith respect to the eye 117 of the lever 97. Accordingly, the lubricant from flexible tube 113 enters pin 115 and flows outward to lubricate the bearing 109, which is thence drained through duct 114 to the bore of pin 116 from which is lubricated the pivot bearing 117, the excess from which passes as in Fig. 1 through pipe 69' to lubricate bearing 98 from which duct 71' leads lubricant to bearing 98'.

The construction of Fig. 2a is modified at pin 115 by providing a shallow circumferential groove 336 thereabout in communication at its lowermost point with the longitudinal bore 105 in arm 94. By this arrangement, not all of the lubricant to pin 115 passes onward through link 114, but a part flows around groove 336 and down bore 105. Bore 105 delivers to a substantially vertical radial bore 330, in shaft 82, which communicates with a longitudinal bore 331, in turn, delivering to horizontal radial bore 332. Bore 332 is aligned with a bore 333 in bracket 78 which delivers to the lowermost part of bushing 81 and through a hole 334 in said bushing upward to bearing 81. A flat 335 on shaft 82

assures alignment with the bore 333 for all positions of the rockshaft 82, so that the lubricant is reliably transmitted, part wiping past said flat to lubricate bushing 80. The duct 333 slopes downward, as shown, so that any lubricant from duct 332 passes on to bearing 81.

The flexible conduit 113 may comprise so-called Bowden wire sheath (Fig. 5a) which includes merely two closely wound small helical springs 118 and 119 wound one about the other. A preferred terminal for the lower end of said duct, comprises a ferrule 122 soldered to the extremity of the duct and has a flange 121 at its lower end pressed by the end of a gland nut 120 thereabout against the bottom of a lateral socket 123' in lug 123 of lever 94, into which the gland nut is threaded. A similar construction of terminal (not shown) may be provided at the upper end. It will be understood that the flexible conduit is not intended to sustain pressure, the fitting 111 being preferably of type such that the pressure from the source is not transmitted therebeyond, and the lubricant merely trickles or flows through the conduit by gravity head and without substantial leakage.

In Figs. 7, 7a and 7b is shown an alternative arrangement for lubricating the two bearings of each of the rock shafts of the construction shown in Fig. 6 and without regard to lubrication of other bearings in the linkage. The rock shafts and their supporting brackets bear the same reference numerals as the corresponding elements in Fig. 6 primed, however. In this construction, bracket 86' is formed with a socket 125 for a lubricant inlet fitting 126, which may be a drip plug, the latter supplied from a pipe 126' from the rear axle or from the torque arm (not shown). According to the present construction, drip plug 126 supplies lubricant reliably to the bearing surfaces of all four bushings 84', 85', 80' and 81'. For this purpose, the bracket 86' is provided with a longitudinal bore having three segments 127, 128 and 129, passing through the bearings 84' and 85' and plugged at its extreme end 129 as at 130.

The bushing 84' is provided with an exterior eccentric groove 131 extending substantially only on the upper half thereof, and providing a path therealong for lubricant from bore 127 to bore 128, which latter delivers through an aligned aperture 134' in bushing 85' to lubricate the corresponding bearing 85' of shaft 83'. Part of the lubricant passing along groove 131 flows downward by gravity through bore 134 in the bushing 84' into an aligned radial bore 133 in the shaft 82'. The shaft 82' is provided with a flat 133' adjacent to the bore 134 so that a portion thereof in all positions of the shaft will be aligned with said bore to intercept some of the lubricant, to supply the bearing of bush-

ing 84'. The bore 133 communicates with a longitudinal or axial bore 135, which extends the length of the upper shaft 82' and delivers into a bore 138 in said shaft, thence through a bore 140 in bushing 80' which, in turn, through an oblique bore 142 in the bracket 78' delivers lubricant to the bearing of bushing 81' by passing through an aligned hole 144 in said bushing. In this construction also, the shaft 82' is flattened as at 138' so that some of the lubricant passing from the bore 138 to the bore 142 would be intercepted to lubricate the bearing of bushing 80'.

It is preferred to fill substantially the entire length of bore 135 with a metal pin or rod 136, which is but a few thousandths of an inch smaller in diameter than said bore and is kept in position therein by spring-pressed caps 145 in the opposite ends of the shaft. The rod 136 is of reduced diameter at its opposite ends as at 137 so as to avoid substantially sealing the shaft bore with respect to the bore 133 supplying the same or the bore 138 supplied from the same.

In operation, lubricant passed by the drip plug 126 will be forced upward along the eccentric groove 131, a portion thereof dropping through the bore 134 and the rest passing onward to bore 128 to lubricate bearing 85'. The portion that drops through bore 134, in turn, takes two courses, a portion being intercepted at flat 133' to lubricate the bearing 84' and the rest passing into longitudinal bore 133. The rod 136 substantially filling the bore 135, there is but a small effective volume in the length of this tube, maintained in place by capillary action and such lubricant as is forced in at 133, causes the ejection of a corresponding mass at the opposite end through bore 138, part of which is intercepted by flat 138' at bushing 80' and the rest passing onward through bores 140, 142 and 144 to lubricate the bearing surface of bushing 81'.

In Figs. 8 and 9, I have shown an arrangement of pitman rod or tube alternative to that shown in Fig. 1. The arm 146 which is secured to the rock shaft 147 has a ball construction 148 at its lower end, which extends through a corresponding slot 149 into a generally cylindrical terminal 150 screwed as at 151 upon the hollow pitman rod 152. Enclosed within the terminal 150 is a slidably bearing cup 153 urged by a coil spring 154 to press said ball against a complementary cup 155 formed at the inner end of a closure plug 156 threaded and locked into the extremity of the terminal 150. The lubricant is conveyed through a bore 157 longitudinally of the arm 146 plugged as at 158 at its lower end, outward through radial bores 159 and 160 in the ball from which the bearing of said ball is lubricated. The spring 154 effects preferably a tight bearing, so that lubricant will pass from the duct 159 largely into

longitudinal duct 161 in the cup 153. A short length of metal pipe 162 rigidly fixed in the rear end of cup 153 conveys the lubricant onward therethrough to drip into the length of the tube 152. To avoid friction and to accommodate the compression and expansion of spring 154 in operation and adjustment, the pipe 162 has a bearing in a bushing 163 at the extreme end of the tube 152. The lubricant passes onward through the length of the tube to a generally similar construction at the opposite end thereof. In the latter construction, however, the pipe 164 is fixed in a bushing 165 in the end of the pitman tube and slides at its opposite end in the longitudinal bore 166 of the bearing cup 153' which bore delivers in part to the ball bearing and in part into radial bore 159' in ball 148'. The construction of terminal 150' is otherwise identical with that described and similar parts bear the same reference numerals primed. Radial duct 159' delivers lubricant to duct 147' in the lever 167, which latter corresponds to either lever 17 of the external brake or lever 28 of the internal brake in Fig. 1. Some of the lubricant from bore 159' will, however, pass through bore 160' to lubricate bearing cup 155'. While the spherical or ball bearing construction shown is preferred, it will be understood that the bearings 148 and 148' may be cylindrical rather than spherical.

It is preferred to provide a boot about each of the terminals in Fig. 8 for the purpose of preventing the entry of dust at the substantial opening 149. A preferred embodiment of boot shown in this connection includes a sleeve element 168 also of leather about the arm 146 clamped as at 169 and formed in a unit with a generally rectangular blank 170 also of leather partially about the terminal and secured by a complementary sheet metal boot portion 171 at the otherwise uncovered part of the terminal, two pairs of ears 171 of which are clamped together by corresponding bolts 172 to securely grip the terminal.

In Figs. 10, 11 and 12 is shown another embodiment of lubricating linkage, in which the arms and the levers at the respective ends of the pitman link, are metal stampings formed to provide the lubricant passages, special terminals being provided to accommodate such stamped members. The arm on the rock shaft comprises a pair of stampings 173 and 174, each having a longitudinal outwardly protruding embossment 175, thereby determining a longitudinal oil duct therebetween. In order to provide an outlet at the lower end of the duct 175 and yet afford sufficient metal for an adequate bearing thereat, a metal frame 176 is interposed between said stampings and acts as a spacer therebetween. The two stampings and the spacer are assembled into a unitary construction in any appropriate manner, but preferably by

bending tongues 177 integral with one of the stampings about the edge of the other. To afford a secure connection of the composite arm with respect to the rock shaft, so that it rocks as a unit therewith, the individual stampings are provided with reversely bent ends 178 extending outward therefrom, said ends and the main lengths of said links being provided with non-circular, preferably hexagonal eyes 179 corresponding to the similar conformation of the rock shaft.

The pitman 180 formed of a hollow or tubular construction as in other embodiments, has a terminal forging 181 secured in place by a socket 182 threaded over the upper or forward end of said pitman. The terminal includes a generally rectangular box-shaped conformation 183 beyond the tube, sustained in pivoted relation from the eye at the lower end of the composite arm 173-174. Said eye comprises a bushing 184 extending through corresponding openings in the lower ends of the stampings 173 and 174, secured in position by a collar 185 pressed thereon. The bushing 184 fits snugly between the lateral walls 186 of the box-shaped terminal 183, which walls are preferably thickened as at 187, where contacted by the bushing. A pin 188 extending transversely through corresponding eyes in the side walls of the terminal chamber and through the bushing 184 and retained by a cotter pin 189, completes the pivot bearing assembly. A saw kerf 190 transversely of the bushing 184 conveys the lubricant from the longitudinally embossed duct 175 in the composite arm 173, 174 to the bearing surface of the pin 188. The lubricant is admitted to the rock shafts in a manner identical with that shown in Fig. 4, the oblique duct 191 through the rock shaft delivering into the arm 173-174 through the gap between the polygonal shaft and the upper and open end of embossment 175, whence the lubricant flows downward through said embossment and through the saw kerf 190 to the pin bearing 188, the latter draining into the bottom of receptacle 183 which, in turn, delivers longitudinally downward through the tube 180 to the bearing at the lower end thereof.

The lower end of the pitman link has a terminal 192 adjustable substantially as the corresponding terminal in Fig. 1. The lever 193 operated from the pitman is of construction generally similar to that shown at the upper end and before described, modified, however, to adapt it for bearing connection with respect to the eye 194 on terminal 192. For this purpose, the upper ends of the individual stampings 195 and 196 are bent to substantially completely encircle as at 197, the sides 198 and 199 of a rigid yoke of U-shape, embracing the flat sides of the eye 194, a pin 200 transversely through the sides 198 and 199 of the yoke and its encircling

stamping portions 197 and through the eye 194 completing the bearing assembly. The embossments 201 in the links are open at their upper ends as shown at 202 to drain the lubricant from the eye 194 downward to the bearing or bearings to be supplied therefrom. As shown in the drawings, I prefer to employ dust excluding boots 203 and 204 at the opposite ends of the pitman link.

In Figs. 13, 14 and 15 is shown an arrangement for the effective lubrication of the various bearings of the internal or hand brake immediately associated with the wheel or brake drum and more especially with brake linkage of the type indicated in Fig. 1. Corresponding parts bear the same reference numerals as in Fig. 1, primed. Substantially all of the bearings, both those at the exterior and those at the interior of the brake drum are supplied by gravity flow from one or more sources rigidly affixed to the brake shield S, which fittings may be oil cups or may be supplied from the frame through any appropriate system of piping. In the present embodiment, I have shown a metal pipe 205 mounted near the top of the brake shield at the interior thereof, sloping downward and clipped in place at 206 near its lower end, to drip oil to the uppermost bearing pin 207 of the brake linkage. The individual brake links are of special construction to facilitate the passage of the lubricant from the bearing 207 to the other associated bearing pins 208, 209 and 210. For this purpose, link 33' is formed of a felt element f, backed with a metallic stamping m, which imparts to it the structural strength required, and one of the two parallel operating links 31' transmitting the braking impulse from arm 30' to the joint of the toggle, is similarly formed of a felt element f, backed with a metallic stamping m. The eyes e of the felt preferably provide a snug fit with respect to the pins 207, 208 and 209 on which they bear, so that lubricant from the bearing 207 will not readily drip off, but will be drawn by the capillary action of the felt f downward to the bearing surface at the pivot pin 208 along which it spreads, the felt f of operating link 31' drawing the lubricant delivered thereto, by capillary action outward to the bearing 209 thereof. Some of the lubricant will escape from between the ends of the pin 208, before it reaches the felt f of link 31' and flow into a longitudinal bore 211 in toggle link 34' and downward to the pivot pin 210 constituting the lower mount of the toggle.

The bearing pin 212 at the upper end of lever 28' by which it is connected to the clevis 213 at the lower end of the pitman link and the mounting bearing 29' of said lever, which protrudes from the exterior of the brake shield are here lubricated from a fitting on the exterior of the shield through a flexible tube 214 which may be identical with that

shown in Fig. 5a and is connected at one end by a terminal nut 215 to supply fitting 216 and soldered at the other end in a corresponding depression 217 in the head of pivot pin 212. The pin is maintained in position against coming out by a cotter pin 218 so that the bearing surface of said pin is both in the link eye 219 and in the eyes of the clevis jaws 213. The lubricant is conveyed through pin 212 as shown by way of a radial duct 220 and a longitudinal duct 221 delivering through a radial duct 222 to a circumferential groove 223 from which lubricant spreads lengthwise of the pin 212. Lubricant in excess of that intercepted by the bearing is conveyed onward through pipe 224 longitudinally of lever 28' and fitting in corresponding sockets 225 and 226 integral with the upper and lower ends thereof, the upper end of said pipe draining from the lower surface of the pivot pin 212 and the lower end draining into vertical bore 227 in the lever which in turn delivers to an oblique bore 228 in the pivot stud of said lever, said stud draining to the bearing 29' thereof in the brake shield.

In the preferred construction both the linkage just described, at the exterior of the brake shield and the linkage previously described at the interior of the brake shield are lubricated simultaneously from a single fitting of special construction. This fitting comprises a forging 216 having a flange 229 bolted as at 230 to the exterior of the brake shield and provided with an integral inlet nipple 231 supplied from the inlet pipe 232 that leads from the frame and with an outlet nipple 214' to which the upper end of the flexible tube 214 is coupled by the nut 215. The inner pipe 205 is supplied from an elbow fitting 233 threaded from the interior of the brake shield into a corresponding socket 234 in the forging 216 said pipe 205 being connected to the other leg of the elbow by a nut 235. The composite fitting described may be provided with any appropriate flow controlling appliance preferably one of my drip plug constructions to assure division of the lubricant in substantially the proportions desired or required between the bearings at the interior and those at the exterior of the brake shield.

The lever 17' for operating the external brake is shown with a pipe 69' and said lever is preferably lubricated through the length of the operating pitman rod therefor in the manner shown in Fig. 1.

In Figs. 16, 17 and 18 is shown an alternative arrangement of the pitman element of the brake linkage. Instead of the seamless tubular construction previously described, I conform a sheet metal strip by longitudinally bending into a generally rectangular tube 239. The lateral edges of the strip meet at 240 at the top and may be soldered or welded, if desired, although this is not essential.

To form the pivot connection at the upper or forward end of the pitman tube, the upper side thereof is cut away as at 241 and a U shaped yoke 242 is slipped over said end, 5 overlapping the sides 243. A terminal fitting 244 encloses the sides 245 as well as the end of the yoke 242 but is cut away at 246 to straddle the pitman tube and is welded in place at said cut away part. The fitting 10 244 has an integral neck 247 extending upward from the pitman, through which extends the lower end of arm 248 the upper end of which (not shown) is affixed to the rock shaft. The arm 248 has an eye 249 at 15 its lower end fitting snugly between the sides 243 of the pitman tube 239, the assembly being completed by the pivot pin 250 which extends transversely through the terminal fitting 244, the yoke 242 and the sides 243 of the tube 239. Preferably collar 251 encircles the arm 248 directly above the neck 247 and is urged against said neck in dust-excluding relation by a coil spring 252 about the arm and reacting against shoulder 253 integral 20 therewith. A pin 248' through the arm 248 maintains the spring 252 and the collar 251 assembled with respect to the arm 248. Lubricant delivered through longitudinal duct 254 in the arm 248, it will be seen is directly 25 applied to the bearing pin 250 and drops therefrom into the bottom of the terminal, whence it passes onward through the tube to the bearing at the lower end thereof.

At the lower end of the pitman tube, there 30 is preferably a threaded terminal post 255 which may be of the general type shown in Fig. 1, for instance. To attach said post to the rectangular tube, the latter is plugged with a rectangular metal block 256 riveted 35 in place as at 257, the post 255 being formed as an integral extension thereof upon which a suitable terminal socket is adjustably threaded. Preferably, the terminal post extends eccentrically of the block 256, from 40 near the lower face thereof, so that the axial bore 258 through said post and block unit is at a level little above the bottom of the pitman tube to facilitate draining of the latter for effective lubrication of the bearing 45 or bearings which are supplied as in Fig. 1 from the pitman tube.

An alternative embodiment of bearing for the lower or rear end of the pitman tube appears in section at Fig. 19. This construction 50 includes a terminal forging 260, a socket 260' one end of which is threaded upon the lower end of the pitman link and having a generally cylindrical concavity 261 in its lower side, formed midway between the parallel side 55 walls 262 of the forging. The flat end walls 263 of the concavity diverge downward, as shown. Into the concavity 261 extends the upper or eye end 264 of the operated lever 265, the bearing being completed by a pivot 60 pin 266 having a head extending with a slid-

ing fit in a corresponding eye 267 in one side wall of the forging 260, the shank of said pin extending through a corresponding bushing 268 friction-fitted into the opposite side wall of the forging which bushing protrudes inward. A dished spring washer 269 encircling the end of the pin 266, contacts the forging 260 and reacts against cotter pin 270 through the pivot pin to draw the head of the latter against eye 264 and to urge said eye and bushing 268 into contact. It will be apparent that rattle is thus avoided, the wear between the thrust surfaces for eye 264 being automatically compensated for by the expansion of spring 269. The lubricant is conveyed from the pitman tube by a bore 271 from near the lower part of the socket 260', said bore connected through a short vertical tube 272 to deliver into a well or depression 273 in the upper end of the eye 264 which well in turn drains through a bore 274 in the eye to the bearing of the pivot pin. The pivot pin preferably has a peripheral groove 275 thereabout which delivers oil, in part, to lubricate the bearing surface of the pivot pin and in part to duct 276 lengthwise of the lever 265 to supply other bearing surfaces.

In Figs. 20 to 27 inclusive, I have shown a number of alternative embodiments, more especially for the lubrication of the equalizer bar of foot operated brake linkage and associated bearings. A conventional mechanism of this type is shown in the drawings. The frame rock shaft comprises two identical sections, one of which appears at 277, each having a bearing 278. Rigid with rock shaft 277 is a lever 279 extending downward therefrom providing a pivot bearing 280 for a link 281 which extends forward therefrom. The two companion links 281 are connected by the equalizer bar 282 pivoted thereto by pivot pins 284. To the middle of bar 282 is pivoted by pin 285, the tension rod 283 which in turn is connected to the brake operating pedal, (not shown).

Each of the three pivot bearings 284, and 285 of the equalizer bar preferably comprises a clevis such as shown at 286 encircling the bar 282 and a pivot pin 284 through the jaws of the clevis and the corresponding eye 282 in the equalizer bar, and held in place by a cotter pin 287.

In Figs. 20 to 22, I have shown one arrangement for effecting lubrication through separate ducts, of the three bearings. Illustratively one conductor 288 leads through a flow control fitting 289 which may be of the general restriction or drip plug type and is shown mounted on the cross channel frame C. Against the outlet nipple 290 of said fitting there is pressed by screw cap 291 the knotted end 292 of a length of metal cable 288, a preferred form of which is known as airplane cord, said cable drooping downward, its lower end encircling as at 294 the central pivot pin

285 immediately under the head thereof. Metal wire 293, preferably binds the ends of the loop 294 thus formed to effect a permanent eye on the cord. The pin 285 may be formed with a shoulder 295 near its head pressing against the clevis jaw 283' so as to afford a predetermined annular space wide enough to accommodate the loop 294, so that the effectiveness of oil feed will not be impaired by pressure on the loop. It will be understood that the lubricant from the fitting 289 will naturally flow lengthwise of cord 288 to and about the eye, dripping therefrom into the pivot pin bearing 285.

15 I have indicated in Figs. 20 and 22 an arrangement for separately lubricating the end bearings 284 of the equalizer bar. For this purpose, I have provided a flow controlling terminal fitting 296 in a corresponding socket 297 extending obliquely upward into the bearing 278, excess lubricant draining from the bearing through a flexible duct 298 leading from the lower most part of the bearing downward to the corresponding end pivot of 20 the equalizer bar. In the preferred construction shown, I employ a length of metal wire tube similar to that shown in Fig. 5a and heretofore described. The terminal of tube 298 at the upper end which is first applied, 25 comprises a gland nut 299 threaded into the bearing and into which the end of the wire tube is soldered. At the other end, I provide a simple terminal of special construction. This terminal comprises a sheet metal tube 300 telescoped over the end of the flexible conduit and preferably soldered thereto and flattened as at 301 beyond said telescoped end, the extreme end being bent over as at 302 to effect a closure thereat. If desired, a slug of 30 metal 303 may be inserted into the open end of the terminal tube prior to the completion of the flattening thereof, said slug, as best shown in Fig. 23 being securely clamped within the tube by completion of the flattening operation, whereupon the tube and the enclosed slug are perforated as at 304 to form the eye. It will be understood, that the flattening and the perforation may be effected by an appropriate die in a single operation. As 35 will appear clearly in Fig. 22, the terminal 301 is applied in position with substantially the same facility and in substantially the same manner as familiar types of electrical terminals. Lubricant flowing through the pipe 298 will be delivered about the pivot pin 284 whence it passes onward to lubricate the bearing surface thereof. The bearing at the left end is preferably identical with that just described.

40 The lubrication of the bearing 280 connecting the lower end of the arm 279 with the link 281 is preferably effected in either of the manners shown in Figs. 24 or 25. In Fig. 24, it will be seen, that the hub 305 of the lever 45 279 is provided with an oblique bore 306 con-

tiguous to the end of bearing 278, so that part of the lubricant from said bearing will pass through said oblique bore, thence longitudinally downward along the exterior of arm 279 to the bearing 280 at the lower end thereof. 50

In Fig. 25 is shown a fragment of a modified form in which there is interposed between the hub 305' of arm 279' and the bearing 278' a sheet metal ring 307 provided with a lug 308 at the lower end thereof, formed as an eye gripping the upper end of a length of conduit 310 such as airplane cord, which extends downward to the pivot bearing at the lower end of the arm 279' to which it is applied by a terminal (not shown) similar to that at 294 in Figs. 20 and 21. Lubricant from the bearing 278' will flow downward along the lug 308 and thence along the airplane cord 310 to the bearing at the lower end thereof. 55

In Figs. 26 and 27 is shown an alternative embodiment by which the three pivot bearings of the equalizer bar 282' are all lubricated through a single conduit. For this purpose, the lubricant controlling fitting 20 mounted preferably on the channel cross bar C is connected through a flexible conduit 311 which may be of the type shown in Fig. 5a, to the head of the central pivot pin 285 of the equalizer bar. Preferably in this embodiment, the lower end of the conduit 311 extends into a corresponding lateral bore in said head into which it is soldered and leads through ducts 312 and 313 in said pin to the bearing surface thereof. A peripheral groove 314 about the pin communicates with a longitudinal bore through the length of the equalizer bar, one section 315 of said bore extending to the pivot bearing 316 at the right and the other section 317 to the pivot bearing 318 at the left. In this embodiment, I have also shown means for lubricating from a common fitting in addition to the bearings of the equalizer bar just described, the bearing at the lower end of the arm 319 on the cross shaft 320 from which the hand brake is actuated. For this purpose, I have provided a generally T-shaped dividing fitting 321, bolted at 322 to the channel cross frame and having mounted in a socket 323 thereof, the flow control or drip plug fitting 324. The conduit 311 is applied at one branch of the T head by the terminal nut 325 while a similar terminal nut 326 at the other branch of the T head, connects a similar conduit 327 with the head of the pivot pin 328 at the lower end of arm 319, which supports the clevis 329 of the corresponding pitman rod. The pin 328 is bored in manner identical with those heretofore described to effectively supply the lubricant to the bearing surfaces thereof in the link and clevis eyes. 100

105 It will be understood that the arrangement of conduit shown in Fig. 27 may be utilized to deliver lubricant to the upper end of a 110

115 120 125 130

pitman tube such as is shown in Fig. 1, for the purpose of lubricating seriatim, a plurality of bearings in the linkage train as in Fig. 1. Substantially complete lubrication of the hand brake linkage may however be effected, according to my invention, without the use of a hollow pitman link by lubricating the upper or forward bearing of such pitman as shown in Fig. 27, for instance, and lubricating the bearings at the drum by the arrangement best shown in Figs. 13 to 15. It will be understood that an arrangement similar to that shown for lubricating the linkage of the hand brake may be utilized for the lubrication of the foot brake linkage.

I claim:—

1. In a motor vehicle of the type including an axle, a chassis frame and springs therebetween; the combination therewith of an arm pivoted to the frame, depending therefrom and movable in a plane longitudinally of the vehicle, a lever pivoted to one of the axles and movable in substantially the same plane as said arm, a tubular pitman connecting said arm and said lever and having pivot bearings at the ends thereof with respect thereto, means admitting lubricant to the upper end of said arm through a conduit lengthwise thereof for flow to the bearing at the lower end thereof, said bearing draining to and through said tubular pitman to the bearing at the opposite end thereof, and a conduit intercepting the drain from said latter bearing and extending lengthwise of the lever to the axle, whereby said arm, pitman and lever will constitute a lubricant conduit between the frame and the axle, which will accommodate the displacement of the axle relative to the frame in operation.
2. In a motor vehicle, in combination, a frame, an axle, a brake construction thereon, linkage for operating the brake and including a succession of lever and rod elements adapted to accommodate the movement of the axle relative to the vehicle frame, each of said elements having a bearing with respect to the succeeding element in the transmission, and means for conveying lubricant lengthwise of said linkage past said bearings in series to lubricate said bearings.
3. A brake transmission linkage including a series of elements pivotally interconnected as an operative mechanism, a continuous conduit along the length of said linkage, each element of said conduit extending downward from its inlet to its delivery end to provide a continuous course for gravity flow of lubricant therethrough, each of said pivotal connections being in the path of lubricant flow from the element which supplies it to the succeeding element in the linkage train, each of said bearings being constructed and arranged to substantially prevent the leak of lubricant through a path other than into

the conduit associated with the succeeding element of the linkage train.

4. In a brake linkage, in combination, a train of mechanical elements including levers and rods transmitting a braking impulse from a manual operating member to the brake, each of said mechanical elements having a bearing connection with respect to the succeeding element of the train, lubricant conduits extending lengthwise of the several mechanical elements, each supplied from the bearing at the upper end thereof and delivering to the bearing at the lower end thereof, the upper end of each of said conduits extending directly below the associated bearing to intercept substantially all of the lubricant draining therefrom.

5. In a brake linkage for a motor vehicle, in combination, a brake cross shaft, an arm depending therefrom, a lever associated with the brake, a tubular pitman connecting said arm and said lever and having pivot mounts at the ends thereof with respect thereto means admitting lubricant to the upper end of said arm and through a conduit to the bearing at the lower end thereof, said bearing draining to and through said tubular pitman to the bearing at the opposite end thereof.

6. In a brake mechanism for a motor vehicle, in combination, a brake, a pivotally mounted brake lever through which the brake impulse is applied, a cross shaft on the frame, an arm connected to said shaft, a hollow pitman connecting said arm to said lever and having a pivot bearing at each of its ends with respect thereto, a conduit leading from said cross shaft lengthwise of said arm to deliver into the corresponding bearing, said bearing draining into said hollow pitman, said pitman draining into the bearing at the lower end thereof, and a conduit intercepting the drain from said latter bearing and extending lengthwise of the lever to the mounting bearing thereof.

7. A brake operating transmission linkage including a succession of levers and rods having pivoted bearings with respect to each other to form a train, said bearings at successively lower levels, each of said elements having a conduit rigidly associated therewith, communicating in the assembled construction with the bearing at the lower end thereof and supplied from the bearing at the upper end thereof, each of said bearings including a connecting pin joining the associated two linkage elements, the bearing surface of said pins lubricated from the duct leading thereto and draining to the duct lubricated therefrom.

8. A linkage including a pair of mechanical elements, a pin extending transversely through their ends to connect them in pivoting relationship, said pin rigid with one of said elements and having an enlargement adjacent the other of said elements to prevent

separation thereof and means for lubricating said pivot bearing, said means including a duct lengthwise of said first mechanical element into said pin, and a duct longitudinally of said pin delivering outward into the encircling bearing of the other mechanical element, said lubricant ducts being contained entirely within said mechanical elements and said pin and crossing the contacting pin and element surfaces.

9. In combination, a linkage including a pair of mechanical elements having eyes, a pivot pin transversely therethrough, means lubricating the bearing surface thereof, said means including a duct longitudinally through one of said elements into said pin and through said pin to deliver to the interior of the eye of the other of said elements, and means rigidly securing said first eye with respect to said pin, whereby the lubricant is conveyed into said pin without substantial loss said lubricant ducts being contained entirely within said mechanical elements and said pin and crossing the contacting pin and element surfaces.

10. In combination, a linkage including a pair of mechanical elements having eyes, a pivot pin transversely therethrough having a head against one of said eyes and fitting snugly in the other of said eyes, a nut threaded on the end of said pin projecting from said latter eye, a shoulder on said pin against which said nut presses said latter eye, whereby said pin is rigidly fixed at said latter eye and the other eye has an oscillating bearing mount on said pin, and means for feeding lubricant into said bolt from the eye fixed relative thereto and longitudinally through said bolt into the eye bearing on said bolt.

11. In a lubricating linkage, in combination, an arm, a substantially horizontal rod pivoted thereto, said pivot comprising a terminal sleeve on said rod having a transverse eye therein, an eye in said arm and a pivot pin through said eyes, said arm having a lubricant duct supplying said pin, said terminal sleeve having a longitudinal bore below and tangentially incident to the lowermost part of said pin, said rod being hollow and supplying lubricant from said pin to another part of said linkage.

12. In a lubricating linkage, in combination, an arm, a rod hinged thereto, said hinge comprising a terminal sleeve on said rod having a transverse eye therein, an eye in said arm and a pivot pin through said eyes, said arm having a lubricant duct supplying said pin, said terminal having a longitudinal bore substantially tangential with the lowermost part of said pin, said rod being hollow and supplying lubricant from said pin to another part of said linkage, and means clamping said pin with respect to said arm, whereby the bearing surface is confined to the rod.

13. In a motor vehicle, a brake mechanism

of the type including a hand brake and a foot brake, a cross shaft for the hand brake, an arm depending therefrom, a rod pivoted to said arm and extending rearward therefrom, and linkage connecting said rod to the corresponding brake, a cross shaft parallel to said first shaft for the foot brake, an arm depending therefrom, a rod pivoted to said arm and linkage connecting said rod to the corresponding brake, each of the operating connections for said brakes having a lubricant duct extending longitudinally thereof to deliver lubricant in series to the various bearings thereof, and an inlet fitting on the frame supplying all of said bearings, said fitting communicating with said rock shafts in parallel, there being flow controlling means at said inlet fitting to effect a substantially correct division of the lubricant between the two rock shafts.

14. In a lubricated structure, a pin, encircling elements placed side by side on said pin, one bearing on said pin and the other fixed thereto, a lubricant duct within and longitudinal of said pin and cooperating lubricant passages through said elements to supply lubricant to and receive it from said duct, respectively, said lubricant passages extending from opposite sides of said pin and said longitudinal duct extending slantwise through the pin so that it opens on different sides of the pin surface immediately adjacent to the openings of the passages on the inside faces of the encircling elements.

15. In a lubricated structure, a pin, encircling elements placed side by side on said pin, one bearing on said pin and the other fixed thereto, an axial lubricant duct within said pin, cooperating radial bores from adjacent the ends of said duct to the outside surfaces thereof enclosed by said elements, circumferential grooves on the outside of said pin at the openings of said radial bores thereon and cooperating lubricant passages through said elements in communication with each other through said grooves, bores and duct.

16. In a lubricated structure, a pin, encircling elements placed side by side on said pin, one bearing on said pin and the other fixed thereto, a lubricant duct within and longitudinal of said pin and cooperating lubricant passages through said elements to supply lubricant to and receive it from said duct, respectively, an inner annular portion of an adjacent side of one element and a corresponding outer annular portion of the adjacent side of the other element being removed and the remaining annular portions being telescoped to form a dirt excluding structure.

17. In a lubricated structure, a pin, encircling elements placed side by side on said pin, one bearing on said pin and the other fixed thereto, a lubricant duct within and

longitudinal of said pin, cooperating lubricant passages through said elements to supply lubricant to and receive it from said duct, respectively, and circumferential grooves on said pin along both faces of one of said elements, the sides of said element being provided with ledges extending over said grooves.

18. In a lubricated structure, a pin, encircling elements placed side by side on said pin, one bearing on said pin and the other fixed thereto, a lubricant duct within and longitudinal of said pin, cooperating lubricant passages through said elements to supply lubricant to and receive it from said duct, respectively, and means at each end of the pin and rigid therewith holding said elements thereupon, said pin being intermediately shouldered to assist in the positioning of the elements thereupon.

19. In a lubricated structure, a shouldered bearing pin, the smaller end of which is threaded, encircling elements placed side by side on said pin on opposite sides of said shoulder, the one on the portion of smaller diameter being fixed to the pin and the other bearing thereupon, a nut upon the threaded end of the pin tightly clamping said fixed element against said shoulder, a lubricant duct within and longitudinal of said pin from within said fixed element to within said bearing element and in communication with said bearing and a cooperating lubricant passage through the fixed element supplying lubricant to said duct.

20. In a lubricated structure, a pin, the ends of which are respectively enlarged and threaded, encircling elements placed side by side on said pin, the one being fixed to said pin and the other bearing on said pin and lubricant passages within said pin and said elements, said enlargement on the end of said pin fitting within a recess in the adjacent side of the adjacent encircling element.

21. In combination, an eye, a bearing pin therethrough and rigid therewith, an eye member encircling said pin, said pin being provided with enlarged annular structures rigid therewith and contacting with the side faces of said eye member and said eye member having ledge portions extending beyond and over the contacting enlargements.

22. In combination, an eye, a bearing pin therethrough and rigid therewith, an eye member encircling said pin, said pin being provided with enlarged annular structures rigid therewith and contacting with the said faces of said eye member and also having peripheral grooves outside of said annular structures and said eye member having ledge portions extending beyond and over the contacting enlargements and partially overlapping said peripheral grooves.

23. A linkage train including a succession of mechanical elements, each having a bearing with respect to the subsequent one, a

continuous oil duct lengthwise of said train contained within said mechanical elements and passing through the bearing surfaces thereof, each of which is constructed and arranged to substantially prevent the entry of dust thereto into the course of the oil flow.

24. A linkage train including a succession of mechanical elements, each having a bearing with respect to the subsequent one, a continuous oil duct lengthwise of said train contained within said mechanical elements and passing through the bearing surfaces thereof, the oil duct of each of said mechanical elements supplied from the bearing surface with respect to the preceding element and delivering to the bearing surface with respect to the subsequent element of the train, each of said bearings constructed and arranged to substantially prevent the entry of foreign particles into the course of oil flow.

25. A linkage train including a succession of mechanical elements, each having a bearing with respect to the subsequent one, a continuous lubricant duct lengthwise of said mechanical elements contained within said mechanical elements and passing through the bearing surfaces thereof, the oil duct of each of said mechanical elements supplied from the bearing surface with respect to the preceding element and delivering to the bearing surface with respect to the subsequent element in the train, each of said bearing elements having metallic structure at the ends thereof affording only a circuitous path for the entry of foreign particles to the bearing surface thereof.

26. In a brake linkage, in combination, a train of mechanical linkage including levers and rods transmitting a braking impulse, each of said mechanical elements having a bearing connection with respect to the succeeding element of the train, lubricant conduits extending lengthwise of the several mechanical elements, each supplied from the bearing at one end thereof and delivering to the bearing at the other end thereof, the adjacent relatively rocking ends of the elements of each of said bearings including telescoping or overlapping structure to substantially preclude the entry of foreign particles to the course of oil flow.

27. A linkage train including a plurality of mechanical elements, each having a bearing with respect to the subsequent element in the train, each of said elements having a bearing pin tight thereon at one end thereof and a bearing eye encircling said pin at the corresponding end of the adjacent element, lubricant ducts lengthwise of said mechanical elements contained within said mechanical elements and passing through the bearing surfaces thereof, each delivering into the pin at one end thereof and from the pin outward into the coating bearing eye, each of said eyes draining to the lubricant duct of the corre-

sponding mechanical element, each of said bearing pins having rigid therewith metallic structure in telescoping relation with respect to the end faces of the bearing eye to substantially prevent the entry of foreign matter into the course of lubricant flow.

28. In a mechanical linkage, in combination, a transmission element having bearings at its opposite ends with respect to associated mechanical elements of the linkage, a longitudinal lubricant duct through the length of said linkage contained within said mechanical elements and passing through the bearing surfaces thereof communicating with the bearings thereof and metallic overlapping structure at the adjacent relatively rocking ends of the elements of each of said bearings, to substantially preclude the entry of foreign particles to the course of oil flow.

20 Signed at New York city, in the county of New York and State of New York this 23rd day of December, A. D. 1924.

JOSEPH BIJUR.
